UNITED STATES PATENT OFFICE.

CHARLEY E. SUMMERS AND FORREST I. COWDERY, OF NOWATA, OKLAHOMA.

WRENCH.

Application filed August 21, 1922. Serial No. 583,358.

To all whom it may concern:

Be it known that we, CHARLEY E. SUMMERS and FORREST I. COWDERY, citizens of the United States, residing at Nowata, in the county of Nowata and State of Oklahoma, have invented certain new and useful Improvements in Wrenches; and we do declare the following to be a full, clear, and exact description of the invention, such as will enable others skilled in the art to which it appertains to make and use the same.

Our invention relates to the so-called fourth connecting rod wrenches designed primarily for use upon Ford automobiles, and the invention relates also to a wrench of this character in which a ratchet head is removably connected by a friction joint with an ordinary nut-receiving socket. It is well known that when wrenches of this type are used on overhead work, the socket tightly engages the nut being turned and will not easily drop therefrom, but the portion of the tool below the socket is prone to lower by gravity and thus become disconnected from the socket. It is an object of our invention however, to provide a handle for the ratchet head having a horizontal portion to rest and oscillate on the upper side of the crank case bottom when in use, so that such an occurrence is impossible.

Another object is to provide a wrench which may be easily and inexpensively manufactured and marketed, yet one which will be highly efficient and in every way desirable.

With the foregoing in view, the invention resides in the novel subject matter herein-after described and claimed, the description being supplemented by the accompanying drawings.

Figure 1 is a side elevation partly in section showing the application of our wrench to the fourth connecting rod bearing of a Ford automobile motor;

Fig. 2 is an enlarged side elevation partly in section, showing the socket and the ratchet mechanism for driving the same; and

Fig. 3 is a sectional view as indicated by line 3-3 of Fig. 2.

In the drawings above briefly described, the numeral 1 designates a U-shaped rod whose arms 2 and 2^a are preferably parallel with each other. The arm 2 is secured in any preferred manner to an L-shaped

head 3 containing a short rotary shaft 4 at 55 right angles to the arm 2, said head being also provided with a reversible ratchet mechanism 5 for driving the shaft 4 in either direction in the same manner as an ordinary ratchet brace. The outer end of the shaft 4 60 is preferably of rectangular form and is here shown provided with a spring pressed ball 6 adapted to retain any one of a number of sockets 7 upon the shaft.

The arm 2^a of the U-shaped rod 1 is bent 65 laterally at its free end to provide an outwardly extending hand grip 8 in axial alignment with the socket 7 and its driving shaft 4, and after forming this hand grip, the arm is bent at right angles as indicated at 9, is 70 then turned upon itself as at 10 and extended beyond the opposite side of the hand grip 8, forming a double ended handle.

When the wrench is used in connection with the fourth connecting rod of a Ford 75 automobile motor, it is applied through the oil pan opening as shown in Fig. 1 and after initially loosening one of the nuts N, for instance by holding the hand grip 8 in one hand and using the cranked portion of the 80 rod 1 as a hand crank, or by gripping opposite ends of the handle 9-10-11, with both hands, it will be seen that the ratchet may be used to complete the nut removing operation. Attention may here be directed 85 to the fact that by grasping the handle between the points 10 and 11 with one hand and exerting a braking action on the socket 7 with the other hand, the handle may be rapidly oscillated and thus the nut may 90 be quickly removed. Obviously, a reversal of these operations will again apply the nut when necessary.

When the wrench is used at exposed places where it can be continuously rotated while 95 removing or applying a nut, the intermediate portion of the U-shaped rod 1 is gripped with one hand and used as a crank for turning the wrench while the hand grip 8 is held in the other hand, in the same manner as 100 an ordinary brace is used. When initially loosening the nut or the like or finally tightening the same, it will be seen that both ends of the handle 9-10-11 may be gripped with both hands and thus the desired amount 105 of power may be applied.

As excellent results are obtainable from the details disclosed, they may well be fol-

lowed, but within the scope of the invention as claimed numerous minor changes may be made.

We claim:

- 5 A fourth connecting rod wrench comprising a short-armed L-shaped ratchet head whose vertical arm is provided with a short upstanding squared stub shaft for frictional reception in one end of an ordinary socket, the horizontal arm of said head being surrounded by a ratchet reversing sleeve, a rod having one rectilinear end portion in axial alignment with and secured directly to said horizontal arm of said head to rest and oscillate on the inner side of the crank case bottom and hold the head, stub shaft and rod against dropping from the socket, said rod being bent downwardly at right angles
- 10
- 15

at a point spaced from said head to form a hand crank, said rod being then bent 20 horizontally at right angles under said first-named end portion and then bent downwardly at right angles to form a second hand grip axially aligned with said stub shaft, the rod at the lower end of the second hand grip being bent laterally first in one direction and then in the other to provide oppositely extending handles, all portions of said rod being in a common plane with the arms of said head and the axis of said 25 stub shaft.

In testimony whereof we have hereunto affixed our signatures.

CHARLEY E. SUMMERS.
FORREST I. COWDERY.
